Nelson M. Howard

UNITED STATES PATENT OFFICE.

GEORGE S. TOLMAN, JR., OF WALPOLE, MASSACHUSETTS, ASSIGNOR TO UNITED SHOE MACHINERY CORPORATION, OF PATERSON, NEW JERSEY, A CORPORATION OF NEW JERSEY.

HEEL-BREASTING MACHINE.

1,400,700.

Specification of Letters Patent. Patented Dec. 20, 1921.

Application filed March 26, 1920. Serial No. 363,893.

To all whom it may concern:

Be it known that I, GEORGE S. TOLMAN, Jr., a citizen of the United States, residing at Walpole, in the county of Norfolk and 5 State of Massachusetts, have invented certain Improvements in Heel-Breasting Machines, of which the following description, in connection with the accompanying drawings, is a specification, like reference characters 10 on the drawings indicating like parts in the several figures.

This invention relates to machines for 15 breasting heels, and particularly to machines for forming the breast portions of heels which have a longitudinal curvature, such heels being known as Louis or French heels.

Heels of this kind have been breasted formerly to a large extent by a machine of 20 the type disclosed in United States Letters Patent No. 784,340, granted March 7, 1905, upon application of B. F. Mayo. The machine disclosed in this patent is provided with a horizontal shaft having a rotary cutter 25 upon it and a shoe support movable tangentially of the path of rotation of the cutter, a shoe being held upon the support with its longitudinal median plane parallel to the cutter shaft, and the shoe support being moved 30 to carry the heel across the cutter to cause the cutter to traverse the heel from side to side and to form a breast surface on the heel which is curved longitudinally of the heel. In the machine of the prior patent the 35 cutter blades are inclined to the cutter axis so as to cause the cutter blade to act upon the heel with a scraping cut, that is, the angle between the advance or leading face of the cutter blade and the portion of the 40 breast treated by the cutter is acute. When the heel is lifted to engage the cutter thus arranged, the heel meets the cutter with considerable shock to the cutter which may result in breaking the cutter off, the detached 45 portion flying outwardly with great force due to centrifugal action of the rapid rotation of the cutter, and greatly endangering the operator. Moreover, the scraping action of the cutting edge renders it difficult to 50 cure as clean a cut as is desirable, particularly on the side of the heel where the heel leaves the cutter.

An object of this invention is to provide a machine of this type which, while retaining 55 all the valuable features of the prior

machine, will be entirely safe for the operator and will effect a smooth cut upon the heel.

A feature of the invention consists in an organization including a bladed, rotary cutter, a shoe support, and means for effecting a relative movement of said support and said cutter to cause the cutter to trim the breast of the heel from one side of the shoe to the other side, the blades of the cutter being arranged so that the advance or leading face of each blade as it comes into action is at an obtuse angle to the face of the heel upon which it acts. As shown herein the cutter shaft is horizontal and the work support is arranged for substantially vertical movement to carry the work across the cutter, the planes of the advance faces of the cutter blades being arranged at an angle to the line of the direction of movement of the work support so that the edge of the cutter blade which acts upon the heel is in advance of the opposite or non-cutting edge of the blade and the blades act with a clearing instead of a scraping cut.

As shown herein the cutter is on the end of its shaft and the cutter blades are arranged in planes which diverge with relation to the shaft and, if extended, would intersect the shaft. The blades are also divergent in a direction away from the heel.

These and other features of the invention will appear more fully from the following description when read in connection with the accompanying drawings and will be pointed out in the appended claims.

In the drawing—

Figure 1 is a front elevation of the head of a machine embodying this invention;

Fig. 2 is an end view of a cutter head with 95 which the machine is provided showing its relation to a heel being breasted;

Fig. 3 is a top plan view of the cutter and heel; and

Fig. 4 is a sectional view of the heel and 100 cutter on the line 4—4 of Fig. 3.

Referring to Fig. 1 of the drawing, the numeral 2 indicates the frame of the machine head in which is journaled a shaft 4 arranged to be rotated rapidly by a belt 6 from any 105 suitable source of power. A cutter head 8 is attached to one end of the shaft 4 and is provided with blades 10, 12 which are inclined to the axis of the shaft in such a manner that the planes of the blades, when ex- 110

tended, intersect the shaft. In other words, the blades lie in planes which are divergent with respect to the shaft. A shoe rest is provided against which the shoe is held in the hands of the operator, the rest comprising, as shown, a tread plate 14 having on the edge next the cutter a lip 16 which is elevated slightly from the plane of the tread plate. The tread face of the heel of a shoe is placed against the tread plate 14 with the edge of the top lift resting against the lip 16, the lip serving to locate the heel longitudinally but being of such slight extent vertically of the heel that substantially the entire breast face 15 of the heel is presented for the action of the cutter (Fig. 3). The tread face of the forepart of the shoe rests against a forepart rest 18 which preferably is arranged for adjustment to accommodate lasts of different 20 spring. As shown, the rest 18 is provided with a stem 19 which is held by a split clamp in a member 20 which also carries the tread plate 14. The tread plate 14 and the rest 18 determine the position of the shoe in its longitudinal median plane and the lip 16 locates the shoe longitudinally. It will be observed also that the longitudinal median plane of the shoe is parallel with the axis of the shaft 25 4. The member 20 is adjustably fixed to the upper end of a vertical rod 22 by means of a set screw having a handle 23. By loosening the set screw 23 the member 20 may be rotated about the axis of the rod 22 to vary the relation of the heel relatively to the cutter. 30 The heel engaging face of the lip 16 is arranged in the axis of the rod 22 so that this adjustment does not disturb the position of the breast edge of the top lift which engages it relatively to the cutter. The rod 22 has a 35 long vertical bearing 25 in a bracket 27 secured to the frame and is moved longitudinally by suitable means, for example a treadle, to carry the shoe rest and shoe heel tangentially across the cutter. Each of the 40 cutter blades is contoured, as shown in Fig. 3, to form a Louis or French heel having a longitudinal curvature, a side edge 24 of each blade being sharpened to form the breast face of the heel and the end portion 45 of 26 being sharpened and contoured to form the base portion of the heel. The blades of course act in turn in rapid succession upon the heel, and in order to cause the cutting edges of the blades to act with a clearing cut 50 the blades are arranged in divergent relation relatively to the shaft and heel as previously stated. This relation will be clear from Figs. 2 and 4 where it will be seen that the advance or leading face 28 of each blade 55 is at an obtuse angle to the breast face of the heel while in engagement therewith. The cutting edge has therefore a true cutting action similar to that of the cutting blade of a plane upon a piece of wood as distinguished from a scraping action such as

would result if the advance face of the blade were perpendicular to the breast face of the heel or at an acute angle to it. The blades therefore make a clean cut upon the heel and remove the excess of material very quickly 70 and without excessive strain upon the shoe heel or upon the cutter. Breaking of the cutter blades is thereby avoided and improved results obtained upon the work.

Having thus described my invention, 75 what I claim as new and desire to secure by Letters Patent of the United States is:

1. In a machine for breasting Louis heels, the combination of a rotary cutter having a plurality of cutter blades, and means for 80 supporting a shoe with its longitudinal median plane parallel to the axis of the cutter, said cutter having its cutting faces constructed and arranged at an obtuse angle to the breast face of the heel to cause the cutter to act upon said face with a clearing cut.

2. In a machine for breasting Louis heels, the combination of a bladed rotary cutter, and a work support movable tangentially of 90 the cutter, the blades of the cutter being contoured to cut the breast and base portion of a Louis heel held on said support and said blades being arranged to diverge away from the heel.

3. In a machine for breasting Louis heels, the combination of a shaft, a bladed rotary cutter mounted on the end of the shaft, the planes of the blades when extended intersecting the shaft, and means for presenting 100 a heel breast for the action of the cutter at the periphery of the cutter and at the side of the cutter which is toward the shaft.

4. In a machine for breasting Louis heels, the combination of a bladed rotary cutter, 105 and a work support movable tangentially of the cutter, the blades of the cutter being contoured to cut the breast and base portion of a Louis heel held on said support and constructed and arranged to effect a 110 clearing cut upon the heel breast.

5. In a machine for breasting Louis heels, the combination of a bladed rotary cutter on the end of a shaft, the planes of the blades when extended intersecting the shaft, 115 and means for presenting a heel breast for the action of the cutter at the periphery of the cutter and at the side of the cutter which is toward the shaft to cause the cutter blades to act successively upon the heel with clearing cuts.

6. In a machine for forming the breast of Louis heels, the combination of a shaft, a cutter head on the end of the shaft, cutter blades on the head arranged with the planes 125 of their advance faces divergent with respect to the shaft, and means for relatively moving a shoe and the cutter tangentially of the cutter with the heel of the shoe on the side of the cutter next to the shaft, the 130

cutter blades being contoured to form the breast of the heel with a longitudinal curvature.

7. In a machine for forming the breast of

- 5 Louis heels, the combination of a shaft, a cutter head on the end of the shaft, cutter blades on the head arranged with the planes of their advance faces divergent with respect to the shaft and having peripheral 10 cutting edges and side cutting edges on the sides of the blades toward the shaft, and means for relatively moving a heel and the cutter tangentially of the cutter to cause the peripheral edges to act on the base portion 15 of the heel and the side cutting edges to act on the breast of the heel.

8. In a machine for forming the breasts of Louis heels, the combination of a shaft, a cutter head on the shaft, cutter blades on 20 the head arranged with one side edge in advance of the other, the advance edge being sharpened, and means for moving a shoe tangentially of the cutter with the heel of the shoe on the side of the cutter adjacent 25 to the sharpened edge, said edge being contoured to form the breast of the heel with a longitudinal curvature.

9. In a machine for forming the breasts of Louis heels, the combination of a shoe 30 support, a shaft, a cutter head on the end of the shaft, cutter blades on the head having peripheral cutting edges and side cutting edges on the sides of the blades toward the heel of a shoe on the support and 35 non-cutting edges on the sides of the blades away from the heel, said side cutting edges

being in advance of the non-cutting edges, and means for moving the shoe support to present the heel tangentially of the cutter to cause the side cutting edges to act on the 40 breast of the heel.

10. A heel breasting machine having, in combination, a rotary cutter comprising blades inclined to the axis of rotation, a work support, and means for moving relatively the cutter and work support to cause the cutter blades to act on the heel breast with a clearing cut. 45

11. A heel breasting machine having, in combination, a rotary cutter comprising 50 blades having end and side cutting edges, a work support, and means for relatively moving the cutter and work support to cause the side cutting edges of the blades to act on the heel breast with a clearing cut. 55

12. A heel breasting machine having, in combination, a rotary cutter head, blades arranged tangentially of the head in planes making equal and opposite angles with the axis of rotation of the head, and means for 60 presenting a heel breast to the convergent sides of the blades.

13. In a machine for breasting heels, the combination of a rotary cutter having cutting edges arranged relatively to the cutter 65 and the heel to effect a clearing cut on the heel breast, and means for guiding the heel in a rectilinear path relatively to the cutter to cause the cutter to breast the heel.

In testimony whereof I have signed my 70 name to this specification.

GEORGE S. TOLMAN, JR.
